William H. Schoonmaker Inventor
By his Attorney
Frank D. Kent

UNITED STATES PATENT OFFICE.

WILLIAM H. SCHOONMAKER, OF MONTCLAIR, NEW JERSEY.

HEADLIGHT.

Application filed September 20, 1921. Serial No. 501,919.

To all whom it may concern:

Be it known that I, WILLIAM H. SCHOONMAKER, a citizen of the United States, residing at Montclair, in the county of Essex 5 and State of New Jersey, have invented certain new and useful Improvements in Headlights, of which the following is a specification.

The present invention relates particularly 10 to headlights for motor vehicles.

The objects of the invention are to eliminate the glare ordinarily experienced with lights of this character, including that occasioned by the lamp filaments and to 15 concentrate the light to the fullest possible extent on the road.

In the accomplishment of these objects I have evolved a headlight having certain 20 novel features of construction, combinations and relations of parts as disclosed in the following specification and illustrated in the accompanying drawing.

In the drawing referred to, I have illustrated typical embodiments of the invention 25 in which Figures 1 and 2 are longitudinal sectional and front views respectively of one form of the invention, and in which

Figure 3 is a longitudinal sectional view 30 of a slightly modified form of the device.

In both the forms shown, the lamp house or casing 5 is made rectangular and substantially square, having the upper portion 35 of its front end open to provide a rectangular outlet 6 for the beam of light and the lower portion of such front end covered by an upright wall 7 of a height sufficient to extend above the filament of the lamp.

The lamp is indicated at 8, and the same 40 is suitably supported in the bottom of the casing with its filament below the upper edge of the blind or shield 7 so that such filament will not be visible from the front of the lamp structure.

The reflector which is located over and 45 in back of the lamp consists of a series of concave reflector strips 9, 10, 11 and 12 offset one in front of the other and each arranged to reflect the light which it collects substantially horizontally so as to form 50 a beam whose constituent rays are substantially horizontal, as indicated by the lines 9^a, 10^a, 11^a and 12^a. These reflector strips may constitute in effect the offset sections 55 of the upper half of a parabolic curve.

In the first form of the invention, the lamp is shown as set quite closely behind

the filament covering shield, whereas, in the second form, the lamp is set further back and the reflector sections are inclined more nearly parallel to the horizontal. With this 60 latter form, on account of the reduced angle of the reflecting faces, the possibility of any glare resulting from looking directly at the reflecting surface, is lessened.

The lower half of the lamp in the illustration, is silvered or provided with a suitable reflector 13 so as to reflect the light emanating from the front of the lamp backwardly and upwardly against the beam reflecting strips.

In both the forms illustrated, the lamp is supported in a forwardly inclined position so as to expose a full clear half of the lamp to the reflector, the lamp socket 14 being for such purpose set at an incline, 70

such as indicated.

The reflector strips preferably extend straight across the entire width of the lamp casing so as to collect all possible light and so as to transmit a wide horizontal light 80 beam. Aside from the reflecting strip, the entire interior of the lamp house is preferably darkened. This darkening may even extend to the narrow connecting strips 15 which connect the adjoining offset ends of 85 the reflector strips. By tilting the lamp body or by varying the angle of the reflector strips, the beam of light may be inclined to strike the road at the proper angle, the filament shielding wall and the lamp reflector 13 being of sufficient extent to prevent exposure of the filament at the front 90 of the lamp when the lamp is thus tilted.

What I claim is:

1. A headlight construction comprising a 95 lamp casing having a substantially rectangular outlet for the beam of light and a lamp shield at the lower edge of such outlet, a lamp in back of said shield and a reflector at the rear of the lamp and consisting of a series of concave reflecting strips 100 arranged in offset relation and extending substantially horizontally and straight across the lamp casing, whereby to provide a beam of light of uniform width in its vertical dimensions but having a diverging formation in its horizontal dimensions.

2. A headlight construction comprising a lamp casing having a substantially rectangular outlet for the beam of light, a 110 lamp shield at the lower edge of such outlet, a lamp at the rear of said shield and a

reflector at the rear of the lamp and consisting of a series of concave reflecting strips arranged in offset relation and extending substantially horizontally and straight across the lamp casing whereby to provide a beam of light of substantially uniform width in its vertical dimensions but having a fan-like diverging formation in its horizontal dimensions, and a reflector covering the forward side of the lamp and arranged to reflect the light emanating from the forward side thereof rearwardly against the beam reflecting strips.

3. A headlight construction comprising a lamp casing having a substantially rec-

tangular outlet for the beam of light and a lamp shield at the lower edge of such outlet, a lamp at the rear of said shield and a reflector at the rear of the lamp and consisting of a series of concave reflecting strips arranged in offset relation, said lamp being set in a forwardly inclined relation to thereby expose a full clear side of the same to the reflecting strips and the lower forward side of the lamp being covered by a reflecting medium.

In testimony whereof I affix my signature.

WILLIAM H. SCHOONMAKER.
